(57) **CLAIM**

The ornamental design for a transparent alcohol brewing system as shown and described.

DESCRIPTION

FIG. 1 is a front perspective view of the transparent alcohol brewing system showing the design;

FIG. 2 is a front view thereof;

FIG. 3 is a back view thereof, opposite the front view of FIG. 2;

FIG. 4 is a first side view thereof;

FIG. 5 is a second side view thereof, opposite that shown in FIG. 4;

FIG. 6 is a top view;

FIG. 7 is a bottom view;

FIG. 8 is an enlarged view of the transparent brewing vessel or kettle shown in FIG. 1 labeled C, shown separately for clarity of illustration of the claim.

FIG. 9 is another enlarged view of the transparent brewing vessel or kettle shown in FIG. 1 labeled C, shown separately for clarity of illustration of the claim.

FIG. 10 is an enlarged view of the transparent brewing vessel or mash/lauter tun shown in FIG. 1 labeled E, shown separately for clarity of illustration of the claim.

FIG. 11 is another enlarged view of the transparent brewing vessel or mash/lauter tun shown in FIG. 1 labeled E, shown separately for clarity of illustration of the claim; and,

FIG. 12 is a partial enlarged view of the transparent brewing vessel or mash/lauter tun shown in FIG. 1 labeled E having a bottom opening, shown separately for clarity of illustration of the claim.

(Continued)

The broken lines in the drawings illustrate portions of the article that form no part of the claimed design.
